PARAFFIN CLEANER FOR OIL WELLS

Cuthbert A. Still and Lawrence M. Still, Alta Loma, Tex.; Lawrence M. Still assignor to Aldrich C. Still, Alta Loma, Tex.

Application July 8, 1939, Serial No. 283,505

10 Claims. (CL. 166—18)

This invention relates to apparatus for use in connection with the drilling of oil wells and pertains particularly to an improved paraffin cleaner, the present application constituting a continuation in part of our prior allowed application, Serial No. 251,806, filed January 19, 1939.

The primary object of the present invention is to provide a novel and improved paraffin cleaner for oil wells which is so designed that it may be inserted without difficulty into the well pipe and passed through the paraffin deposit therein, even though such deposit may be relatively thick, so that only a small passageway remains at the center of the pipe and when drawn back, will present for engagement with the body of paraffin, a plurality of cleaning or scraping fingers which will effectively remove all of the paraffin from the surface of the pipe, starting at the lower end of the deposit and working upwardly through the well pipe.

Another object of the invention is to provide in a paraffin cleaner of the above described character, a central body carrying a series of scraper fingers which are so designed and arranged upon and about the body that when they are in operative position, they will present a fan-like arrangement around the body which will clean out the well pipe in one operation of moving the device from the lower part of the paraffin deposit upwardly, if no obstructions on the wall of the pipe are encountered.

Still another object of the invention is to provide in a device of the above described character cleaning or scraping fingers which are in the form of flat strips or bands of resilient material which, in the event that an obstruction is encountered in drawing the device through the well pipe, will flex or yield so that the device may come through without having any of the scraper fingers damaged, such fingers after passing the obstruction returning to their former straight condition by reason of their resiliency.

Other advantages of the invention will become apparent as the description of the same proceeds and the invention will be best understood from a consideration of the following detailed description taken in connection with the accompanying drawing forming part of this specification, with the understanding, however, that the invention is not to be confined to any strict conformity with the showing of the drawing but may be changed or modified so long as such changes or modifications mark no material departure from the salient features of the invention as expressed in the appended claims.

In the drawing:

Figure 1 is a view in elevation of the upper portion of the rod or body per se of the present tool, illustrating the arrangement of the finger receiving recesses thereabout.

Figure 2 is a view of the upper portion of the implement with parts broken away to show details of construction.

Figure 3 is a sectional view taken transversely of the implement above the fingers and looking longitudinally of the body to show the working arrangement of the fingers when in the well casing.

Figure 4 is a transverse section taken above and looking toward one of the working fingers.

Figure 5 is a detailed fragmentary view illustrating the manner in which the finger is adapted to flex under strain.

Figure 6 is a view illustrating a modified form of the working or scraping finger and the mounting therefor.

Figure 7 is a view in perspective of the modified scraping finger per se.

Referring now more particularly to the drawing, the numeral 1 generally designates the body of the present paraffin cleaner or scraper device, which body is in the form of a steel rod or shaft of suitable diameter which at its lower end is provided with a threaded reduced extension by means of which the device may be connected with a sinker rod if desired.

At the upper end of the body 1 a similar reduced extension 3 is formed which is exteriorly threaded and is adapted for connection with an adapter 4 which comprises an elongated body of the same overall diameter as the rod body 1 and which has a central bore 5 therethrough which at its lower end merges with the enlarged interiorly threaded socket 6 in which the extension 3 is threadably secured. The bore 5 is designed to receive a suspension cable, the lower end of which is secured by the extension 3 against the inner end of the socket 6, so that the cleaner device may be raised and lowered by such cable.

In order that the coupling between the adapter 4 and the upper end of the body 1 may be made secure, there is provided a locking key 7 which is passed through a slot 8 in the lower end of the adapter 4 for engagement in a socket or recess 9 in the side wall of the extension 3 and there is then threadably secured to and about the lower end of the adapter, the collar 10 which covers the key 7 and holds it in place.

In carrying out the present invention, the rod body 1 is provided with a spirally arranged series

of milled slots, each of which is indicated by the numeral 11, which slots extend in a longitudinal direction on the rod and are slightly offset in their spiral arrangement around the rod, as shown.

5 In and adjacent the lower end of each slot 11, a stop body 12 is secured by welding or in any other suitable manner and extending transversely of each slot adjacent the inner side thereof and slightly above the top of the stop body 12 is a 10 transversely extending pivot pin 13.

10 Each of the pivot pins 13 passes through an eye 14 which is formed at one end of a scraper finger 15 which swings freely upon the pin 13 and when swung outwardly and downwardly thereof, rests 15 upon the top of the adjacent block 12 so that it will be held outwardly extending from the rod and perpendicular thereto in the manner illustrated. Each of these fingers 15 is in the form of a short flat strip or ribbon of spring metal 20 and each is designed to lie substantially entirely within its slot 11 when it is swung upwardly on its pin 13. By this means the rod can be easily inserted into a well even though such well may have a thick deposit of paraffin upon the inner 25 wall of the well pipe so that there is only left a small central passage through which the rod can pass. Since there are no obstructions on the rod and the spring fingers swing upwardly into substantially a flat position at the side of the rod, 30 it will be readily seen that the rod may easily slip downwardly of its own weight past a thick paraffin deposit.

35 The length of the spring fingers is such that when all of the fingers are in down or operative position with the rod 1 at the center of the drill pipe, the outer ends of the fingers will come into close proximity with the wall of the pipe. In addition to this, by arranging the spring fingers spirally around the rod and offsetting each one 40 only slightly from the adjacent ones, the fingers will have an overlapped operating relation such that their outer ends will form or cut side by side parallel paths through the paraffin deposit as the device is drawn upwardly through the well 45 and thus if no obstructions are encountered by the fingers in drawing the device through the well, all of the paraffin will be removed from the inner surface of the pipe in the one operation of pulling the device up through the well 50 posit. The arrangement of the spring fingers when all are in operative position and when viewing the same from the top of the cleaner, that is, when looking lengthwise of the rod from the top thereof, is as illustrated in Figure 3, wherein it 55 will be seen that the fingers form a complete collar around the rod which at its outer periphery conforms to the curvature of the well pipe.

60 In Figures 5 and 6 there is illustrated a slightly modified form of the finger structure 15. In Figure 5 a portion only of the finger carrying body is illustrated, this body being indicated generally by the numeral 16. It will be understood that this body 16 is of the same construction as the body 1 in that it is provided with a 65 plurality of recesses or slots 17 corresponding with the slots 11 and arranged in the same order in the body 16 as the slots 11 are arranged in the body 1.

70 The lower end of each of the slots 17 is formed to provide an abutment wall 18 and just above this wall there extends transversely of each slot 17 a pivot pin 19 on which is oscillatably supported the modified scraper finger, which is here indicated generally by the numeral 20. This 75 modified scraper finger is formed of a stiff re-

silient wire or bar material and has the body portion 21 which terminates at one end in the flattened scraper blade 22. At its opposite end, the body merges with the coil 23 which performs the double function of a spring and a sleeve corresponding with the sleeve 14 of the finger 11. The end of the coil opposite that to which the body 21 is joined terminates in the stop finger 24 which is substantially perpendicular to the body 21. The pivot 19 extends through the coil 10 sleeve 23 and the stop finger 24 bears against the shoulder 18 when the finger is extended outwardly from the body 16, as shown in Figure 5. It will be readily obvious that when the tool is introduced into the well hole, the finger 20 will 15 oscillate upwardly to enter the slot or recess 17 in the same manner as the fingers 15 move into their recesses 11, thus permitting the tool to slip down into the well.

20 In the use of the present tool, the body of the tool will be lowered into the well below the paraffin deposit by means of a cable connected with the adapter at the upper end of the tool body and in being lowered the finger 15 or 20 will be swung upwardly or closed by contact with the paraffin wall as the tool moves downwardly, thus permitting the tool to move into working position easily and smoothly. After the device has been lowered to the desired position beneath the paraffin deposit or to the desired position 30 in the paraffin deposit, the teeth will swing outwardly so that their outer ends will engage against the wall of the deposit and when the tool is then drawn upwardly the ends of the teeth will dig into the deposit of paraffin and this will cause 35 them to move into positions where they will be perpendicular to the body to which they are pivotally attached. The fingers 15 will be held in this perpendicular position with respect to the body 1 by engagement against the stops 12 which 40 lie beneath them and the fingers 20 will be held in perpendicular relation with the body 16 by the engagement of the stop finger 24 against the wall 18, as shown in Figure 5.

45 Since both forms of fingers are carried upon their supporting bodies in spirally disposed groups, they will present a fan-like arrangement, as illustrated in Figure 3 in connection specifically with the fingers 15, and thus as the tool is drawn upwardly practically the entire inner surface of 50 the well casing will be engaged by the outer ends of the fingers so that the paraffin will be entirely scraped free.

55 As previously stated, the fingers 15 are of resilient metal so that in the event of any one of them coming into contact with some fixed object in the well the finger will bend down, as shown in Figure 5, and thus permit the tool to be drawn up without breaking the finger.

60 In the modified form of the invention, the spiral 23 operates as a spring to permit the finger to yield, although the finger itself is formed of resilient material and would have some flexibility to yield in a somewhat similar manner to the finger 15. It will be understood, however, 65 that the spiral 23 takes the major portion of the strain and returns the finger to a horizontal position after the interfering object has been passed. It is to be understood, however, that the spiral 23 also functions as a supporting sleeve 70 and that, therefore, where the claims call for a sleeve-like portion, the spiral 23, as well as the part 14 of the finger 15, is to be understood.

75 The cable used in connection with devices of this kind is tested to carry approximately 900 75

5 pounds weight but it is not permitted to suspend from the cable a weight of more than 500 pounds. With other types of devices where no resilient tooth action is had, if the scraping teeth should encounter an obstruction, the pull or weight upon the cable would, of course, be greatly increased and might result in the breaking of the cable with the loss of the scraping tool and consequently the well would be choked. By providing the 10 resilient scraper fingers and tempering the same so that they will yield or bend under a strain of approximately 500 pounds, it will be seen that if an obstruction is encountered by the fingers and the strain thereon exceeds 500 pounds, the fingers 15 will bend and thus permit the tool to come up through the pipe and avoid breaking the cable. While such action would result in only a partial cleaning of the pipe, it will be readily apparent that the tool can be again lowered and raised 20 until the cleaning operation is completed.

What is claimed is:

1. A paraffin cleaner for oil wells, comprising a rod body, means for attaching a cable to one end of said body, a plurality of fingers pivotally attached to the body in a spiral order thereabout to oscillate longitudinally of the body from positions where they extend toward the said end to normal working positions in which they are perpendicular to the body, means for supporting the 30 fingers in perpendicular relation to the body, said fingers having an inherent resiliency whereby they may flex downwardly from said normal perpendicular position upon the application of a pressure of predetermined force thereto.

35 2. A paraffin cleaner for oil wells, comprising an elongated body having means at one end for the attachment of a supporting cable thereto, said body being provided with a spirally arranged series of outwardly opening slots, a pivot 40 pin extending transversely of each slot, a spring finger pivotally mounted at one end upon each pin, and means in the slot below the finger forming a stop for the adjacent finger whereby the finger will be normally retained in a position perpendicular to the body, each finger being adapted to swing upwardly on its pivot pin into the slot.

45 3. A paraffin cleaner for oil wells, comprising an elongated body having means at one end for the attachment of a supporting cable thereto, said body being provided with a spirally arranged series of outwardly opening slots, a pivot pin extending transversely of each slot, a spring finger pivotally mounted at one end upon each pin, and means in the lower end of each slot 50 forming a stop for the adjacent finger whereby the finger will be normally retained in a position perpendicular to the body, each finger being adapted to swing upwardly on its pivot pin into the slot, each of said fingers being in the form 55 of a flat strip of resilient metal which is tempered to flex upon the application to the outer end thereof of a predetermined pressure.

60 4. A paraffin cleaner for oil wells, comprising a rod having means at one end for the attachment of a suspension cable thereto, a series of flat finger members arranged in a spiral order around the rod and each pivotally attached to the rod, means adjacent each finger forming a stop whereby the finger will be held in a working position perpendicular to the rod, all of the fingers being adapted to swing in the same direction to a position substantially parallel with the rod, and said fingers being spaced in said spiral order so that they will have a progressive overlapping working relation.

5 5. A paraffin cleaner for oil wells, comprising a rod member, means at one end for the attachment of suspension means thereto, said rod member being provided with a spirally arranged series of longitudinally extending slots, adjacent slots having their ends in overlapping relation, a pivot pin extending transversely of each slot, a flat spring finger for each slot having a transverse sleeve at one end through which the pivot pin of the slot passes, stop means in the lower part 10 of each slot below the plane of the pivot pin for supporting the spring finger in outwardly extending position perpendicular to the rod, the spring fingers being designed to swing all in the same direction into their respective slots, and 15 said slots being so disposed in the spiral series that the fingers when in perpendicular relation with the rod will be arranged in overlapping working positions to form a substantially complete scraping collar about the rod. 20

6. In a paraffin scraper for oil wells, including a rod having a spirally arranged series of scraping fingers pivotally attached thereto to extend perpendicularly outwardly with respect to the rod, means for attaching a suspension cable, comprising a reduced threaded extension at one end of the rod, an elongated tubular body having the tubular center enlarged at one end into a socket for the threaded reception of said extension, said tubular body being designed to receive a supporting cable with one end secured in said socket by the threaded extension, and locking means coupling the end of the tubular body with said threaded extension whereby accidental separation of the rod and tubular body are prevented. 35

7. A paraffin cleaner for oil wells, comprising a rod body, means at one end of the body for attaching a suspension cable thereto, said body having a plurality of recesses in the wall thereof arranged spirally thereabout, a resilient finger member for each recess having a sleeve-like portion disposed in the recess, a pivot pin extending transversely of each recess through the sleeve-like portion of the finger member, each of said finger members being adapted to swing in the 40 recess toward the end of the body carrying said attaching means, means whereby when each of said fingers is swung in the opposite direction it will be maintained extended from its recess in perpendicular relation to the body, and means 45 whereby each of said fingers may be resiliently moved in opposition to said retaining means in a direction away from the said cable attaching means. 50

8. A paraffin cleaner for oil wells, comprising a rod body adapted to be lowered into the well, said body having a plurality of recesses in the wall thereof arranged spirally thereabout, a finger member for each recess having a sleeve-like portion at one end constituting a spirally arranged continuation of the finger, the said sleeve-like portion of the finger being disposed in a recess, a pivot pin extending transversely of the recess through the sleeve-like portion of the finger, each of said fingers being adapted to swing 60 in the recess toward the upper end of the body, and means forming a part of the sleeve-like portion for engaging a wall of the recess to maintain the finger perpendicular with respect to the body when the finger is swung outwardly from the body, said spiral-like sleeve forming a yieldable means for permitting the forcible movement of the finger downwardly beyond the said perpendicular position. 70

9. A paraffin cleaner for oil wells, comprising 75

an elongated body adapted to be lowered into a well, said body having a plurality of recesses formed therein and arranged spirally thereabout, a pivot pin extending transversely of the lower 5 part of each recess and a scraper finger for each recess comprising a body of resilient metal formed at one end to provide a spiral spring constituting a sleeve through which a pivot pin passes, one end of said spiral spring being extended in 10 a direction substantially perpendicular to the body portion of the finger to form a stop member adapted to bear against a wall of the recess whereby said finger will be held for a scraping 15 operation substantially perpendicular to the supporting body, the finger being adapted to swing

upwardly into the adjacent recess to permit the body to enter the well.

10. As an article of manufacture, a scraper finger for use in a paraffin cleaner of the character described, comprising an elongated body of resilient metal formed at one end to provide an integral spiral spring sleeve, the longitudinal axis of which extends perpendicular to the finger, said spiral spring sleeve at the end remote from the finger terminating in a short stop finger arranged 10 perpendicular to the first finger, the said first finger having its free end flattened to form a scraping blade.
